UNITED STATES PATENT OFFICE.

MAURICE KANE, OF AUSTIN, ILLINOIS, AND ALBERT GRIEVES, OF SPRINGFIELD, OHIO, ASSIGNORS TO INTERNATIONAL HARVESTER COMPANY, A CORPORATION OF NEW JERSEY.

HAY-STACKER.

No. 800,748.

Specification of Letters Patent.

Patented Oct. 3, 1905.

Application filed May 17, 1905. Serial No. 260,750.

To all whom it may concern:

Be it known that we, MAURICE KANE, residing at Austin, in the county of Cook and State of Illinois, and ALBERT GRIEVES, residing at 5 Springfield, in the county of Clark and State of Ohio, citizens of the United States, have invented certain new and useful Improvements in Hay-Stackers, of which the following is a specification, reference being had to the accompanying drawings, forming a part thereof.

This invention relates to hay-stackers, and particularly to those having hoisting-derricks forming a part thereof.

The invention consists of a base-frame upon 15 which is rotatably mounted a mast suitably supported laterally by braces secured at their lower ends to the base-frame and at their upper ends to a cap-piece forming a bearing for the rotatable mast. A boom is pivotally attached to the mast above the braces and at its outer end has a fork pivotally connected therewith. It projects beyond its pivotal connection with the mast, and a jib is pivotally connected thereto and by a link connection with 20 the mast. A hoisting mechanism is connected with the movable parts of the derrick; and the objects of the invention are to provide a mechanism that will elevate the fork to a higher plane and to provide for a better transmission of power to raise the boom, to improve the construction of the boom whereby its strength and rigidity are increased, to provide improved means for controlling the angle of the teeth of the fork, and to provide 25 improved means for tripping the fork to discharge the load, and to provide means for locking the mast in position when the fork is receiving and elevating the load.

The objects are attained by the mechanism 30 illustrated by the accompanying drawings, in which—

Figure 1 is a side elevation in perspective of a hay-stacker embodying the invention. Fig. 2 is a side elevation of a stacker, showing 45 the operation of the elevating-fork. Fig. 3 is a detail of the rear end of the boom and its pivotal connection with the mast. Fig. 4 is a detail of the fork-tripping mechanism, and Fig. 5 is a section of Fig. 4 on line A B. Fig. 50 6 is an enlarged view of the fork, showing the manner in which it is pivotally connected with the boom; and Fig. 7 is a cross-section on line C D of Fig. 6.

The same reference-numerals represent like parts throughout the several views.

1 is an A-shaped base-frame having cross-sills 2 and 3 at opposite ends thereof and an intermediate cross-sill 4 near its center, upon which is pivotally mounted a mast 5, that is supported laterally by means of braces 6, 7, 8, and 9, secured at their lower ends to the base-frame and at their upper ends to a cap-piece 10, in which the mast 5 is rotatably mounted. Secured to the mast above the cap-piece is a band 11, and a strut 11' forms a part thereof, and 12 is a truss-rod which has its opposite ends secured near the top and bottom of the mast and its middle portion engaging with the strut. The band 11 rests upon the cap-piece, and the weight of the mast and parts carried thereby is supported thereon. Pivotally connected with the mast above the cap-piece 10 is a boom 13, comprising two arms that have their ends connected together at one side of the pivotal connection by means 75 of the casting 14 and diverge outward at their opposite ends, which are pivotally connected with a fork 15 by means of the arms 13', pivotally connected with brackets 14', secured to the cross-bars 15', as shown in Figs. 6 and 7. 80 A cross-bar 16 connects the diverging ends of the boom-bars, and 17 and 18 are additional cross-bars connecting them at intermediate points toward the mast. A jib 19, comprising two bars, one upon each side of the mast, having their lower ends pivotally connected with the casting 14 and having sheaves 20 and 21 at its upper end, is flexibly connected with the upper end of the mast by means of a link 22.

The elevating-fork is one made after a common form, having a rigid vertical standard 23 forming a part thereof, to the upper end of which is attached a cable 24, that passes under a sheave 25, mounted on the cross-bar 17, and upward and over a second sheave 26, mounted 95 upon the mast a sufficient distance above the pivotal connection of the boom therewith to form a parallel-motion device to retain the teeth of the fork in an approximately horizontal position while the fork is being elevated to deposit its load and then downward along the mast to a hand-lever 27, to which it is adjustably secured by means of the link 28, having a series of holes at its lower end to provide for such adjustable connection. Two 100 bars 29 and 30 are secured to the mast upon 105

opposite sides thereof by means of a bolt 31 and brace 32. The hand-lever 27 is pivotally mounted on the end of the bolt 31, and when the fork is in position to receive a load the 5 opposite end of the lever engages with a laterally-projecting part 33, secured to the bars 29 and 30, and by means of the connecting-cable maintains the fork in that position. To trip the fork to discharge the load, it is necessary to disengage the lever 27 from the projection 33.

Pivottally mounted between the bars 29 and 30 upon a horizontal pivot is a sweep-lever 34, and secured thereto inside of its pivotal connection 35 is a strap-bracket 36, having an upward and outward inclined portion 37, adapted to contact with the hand-lever 27 and disengage it from the projecting part 33 when the lever 34 is raised at its outer end, as shown 15 by dotted lines in Fig. 4. The sweep-lever 34, in combination with the bars 29 and 30, has the double function, securing and releasing the fork-controlling means and rotating the mast for the purpose of moving the fork 20 from its receiving to its discharging position. When the fork is in position to receive the load, and while it is being elevated, the mast is locked from turning by means of the hook 38, pivotally mounted on the brace 9 and adapted 25 to engage with the lever and hold it against the brace.

Mounted upon the cross-bar 3 of the base-frame is a power-transmitting means 39, comprising vertical and horizontal sheaves suitably 35 mounted and adapted to guide the rope 40, to which a draft-team is hitched in the usual way. The rope passes over a sheave mounted at the upper end of the mast and is rove through the sheaves mounted at the upper end of the jib 40 and in the block 41, connected to the boom in the well-known manner.

By connecting the boom to the mast above the upper ends of the lateral braces a wider range of movement thereof is obtained, and 45 by connecting the lower end of the jib to the boom beyond its pivot a better transmission of the power is obtained through the downward thrust of the jib as the fork is elevated. By extending the side members of the boom 50 beyond their pivotal connection with the mast and connecting them together by means of the bridge - piece 14 the boom is made much stronger to resist a torsional strain caused by an unequal distribution of the load upon the fork.

The angle of the teeth of the fork relative to the boom may be adjusted by means of the connection between the cable and the hand-lever.

60 What we claim as our invention, and desire to secure by Letters Patent, is—

1. In a hay-stacker, the combination of a base, a mast rotatably mounted upon said base, a boom pivotally mounted on the mast and extending beyond its pivotal connection, a fork

mounted on the boom, and a jib pivotally connected with the extended end of the boom.

2. In a hay-stacker, the combination of a base, a mast rotatably mounted upon said base, a boom comprising two arms pivotally connected at one end with said mast upon opposite sides thereof and extending beyond said pivotal connection, a fork pivotally connected with the opposite ends, and a bridge-piece secured to said extended portions. 75

3. In a hay-stacker, the combination of a base, a mast rotatably mounted upon said base, a boom comprising two arms pivotally connected at one end with said mast upon opposite sides thereof and extending beyond said pivotal connection, a fork pivotally connected with the opposite ends, a bridge-piece secured to said extended portions, and a jib pivotally connected at its lower end with said bridge-piece. 80

4. In a hay-stacker, the combination of a base, a mast rotatably mounted upon said base, a boom pivotally mounted on the mast, a fork mounted on said boom, braces secured at their lower ends to the base and extending upward and inward toward the mast, a cap-piece to which the upper ends of said braces are secured, said cap-piece forming a bearing for the mast below the pivotal connection of the boom therewith. 90

5. In a hay-stacker, the combination of a base, a mast rotatably mounted upon said base, a boom and fork carried by said mast, braces secured at their lower ends to the base and extending upward and inward toward the mast, a cap-piece to which the upper ends of said braces are secured, said cap-piece forming a bearing for the mast near its middle portion, said mast being supported laterally and downwardly by said cap-piece. 95

6. In a hay-stacker, the combination of a base, a mast rotatably mounted upon said base, a boom and fork carried by said mast, braces secured at their lower ends to the base and extending upward and inward toward the mast, a cap-piece to which the upper ends of said braces are secured, said cap-piece forming a bearing for the mast near its middle portion to support it laterally, a band surrounding said mast and resting upon said cap to support the mast downwardly, a truss-rod secured at opposite ends to the mast, and a strut integral with the band and engaging with the middle portion of the truss-rod. 110

7. In a hay-stacker, the combination of a base, a mast rotatably mounted upon said base, a boom having one end pivotally connected with the mast, a fork pivotally connected with the opposite end of the boom, means for retaining the fork in position to receive and elevate a load, comprising a guide-sheave mounted on the mast, a hand-lever pivotally mounted to rotate with the mast, a flexible connection between said hand-lever and fork engaging with said guide-sheave, and locking 120

means to retain said hand-lever in position to support said fork in its receiving and elevating position.

8. In a hay-stacker, the combination of a base, a mast rotatably mounted upon said base, a boom having one end pivotally connected with the mast, a fork pivotally connected with the opposite end of the boom, means for retaining the fork in position to receive and 10 elevate a load, comprising a guide-sheave mounted on the mast, a hand-lever pivotally mounted to rotate with the mast, a flexible adjustable connection between said hand-lever and fork engaging with said guide-sheave, and locking means to retain said hand-lever in position to support said fork in its receiving and elevating position.

9. In a hay-stacker, the combination of a base, a mast rotatably mounted upon said base, 20 a boom having one end pivotally connected with the mast, a fork pivotally connected with the opposite end of the boom, means for retaining the fork in position to receive and elevate a load, comprising a guide-sheave mounted on the mast, a bracket secured to the mast, a sweep-lever connected with the bracket on a horizontal pivot, a hand-lever pivotally mounted on the bracket, and means for locking it therewith, a flexible connection between 25 said hand-lever and said fork engaging with said guide-sheave, and means connected with said sweep-lever to release said locking means when the sweep-lever is rocked about its pivot.

10. In a hay-stacker, the combination of a base, a mast rotatably mounted upon said base, a boom having one end pivotally connected with the mast, a fork pivotally connected with the opposite end of the boom, means for retaining the fork in position to receive and 35 elevate a load, comprising a guide-sheave mounted on the mast, a bracket secured to the mast, a sweep-lever connected with the bracket on a horizontal pivot, a hand-lever pivotally mounted on the bracket, a projection on said bracket adapted to engage with said hand-lever and lock it against movement in one direction, a flexible connection between said hand-lever and said fork engaging with said guide-sheave, and a bracket secured to the inner end of the 45 sweep-lever and contacting with said hand-lever in a manner to move it laterally away from said projection when said sweep-lever is rocked about its pivot.

11. In a hay-stacker, the combination of a base, a mast rotatably mounted upon said base, 55 a boom having one end pivotally connected with the mast, a fork pivotally connected with the opposite end of the boom, means for retaining the fork in position to receive and elevate a load, comprising a guide-sheave mounted on the mast, a bracket secured to the mast, comprising two bars upon opposite sides thereof, a sweep-lever mounted between the bars upon a horizontal pivot, a hand-lever pivotally mounted on one of the bars, a projection on said bar adapted to engage with said hand-lever and lock it against movement in one direction, a flexible connection between 60 said hand-lever and said fork engaging with said guide-sheave, and a strap-bracket secured 65 to the inner end of said sweep-lever and projecting laterally below the bars and upwardly between the hand-lever and the adjacent bar, said upwardly-projecting portion being inclined in a manner to disengage the hand-lever 70 from said projection when the sweep-lever is rocked about its pivot.

12. In a hay-stacker, the combination of a base, a mast rotatably mounted upon said base, braces secured at their lower ends to said base, 80 and at their upper ends to a bearing for the mast, a sweep-lever secured to said mast, and releasable means connecting said sweep-lever with one of said braces.

13. In a hay-stacker, the combination of a base, a mast rotatably mounted upon said base, a boom secured to said mast and having a fork connected therewith to receive and elevate a load, a sweep-lever secured to said mast, and means for locking said sweep-lever against 90 movement when said fork is in position to receive and elevate the load.

14. In a hay-stacker, the combination of a base, a mast rotatably mounted upon said base, braces secured at their lower ends to said base, 95 and at their upper ends to a bearing for the mast, a sweep-lever secured to said mast, and a hook pivotally mounted on one of said braces and adapted to lock said sweep thereto.

In witness whereof we hereto affix our signatures in presence of two witnesses.

MAURICE KANE.
ALBERT GRIEVES.
